UNITED STATES PATENT OFFICE

CESARE BARBIERI, OF NEW YORK, N. Y., ASSIGNOR, BY MESNE ASSIGNMENTS, TO VOR-TEX CUP COMPANY, OF CHICAGO, ILLINOIS, A CORPORATION OF DELAWARE

PRINTING AND CAP FORMING MACHINE

Application filed July 20, 1928. Serial No. 294,180.

In the dispensing of ice-cream and similar frozen commodities in paper containers, it is essential for sanitary reasons, to protect the contents of the containers by means 5 of caps. To identify the product the manufacturer's name plate and trade-mark may be printed on the outer surface of the caps.

This invention relates to an improved cap forming machine adapted to print a moving 10 strip of material and subsequently punch blanks therefrom and then shape the punched and printed blanks into caps adapted to be conveniently inserted in place in ice-cream containers or the like.

15 It is an object of this invention to provide a machine adapted to automatically print a strip of material and then cut out cap blanks from the material.

It is also an object of this invention to provide 20 a machine wherein a strip of material is adapted to be advanced across the field of operation of a rotating printing plate to have the type set-up printed at spaced intervals on the strip of material after which the printed 25 strip is advanced through the field of operation of a punch and former mechanism, whereby printed cap blanks are punched from the material and then formed into flanged caps adapted to be inserted into the open ends of conical ice-cream cups or similar 30 containers.

It is a further object of this invention to provide a machine having a cam controlled 35 ink supply mechanism adapted to ink a rotatable printing plate to cause printed matter to be printed upon an advancing strip of material as it advances through a cam controlled punch and forming mechanism adapted to punch printed cap blanks from the material 40 and then form the blanks into flanged caps ready to be used in ice-cream containers and the like.

It is an important object of this invention to provide a machine adapted to conveniently 45 and economically print and punch cap blanks from a moving strip of material and then form the printed blanks into caps to be used to close ice-cream dispensing containers or the like.

50 Other and further important objects of this

invention will be apparent from the disclosures in the specification and the accompanying drawings.

This invention (in a preferred form) is illustrated in the drawings and hereinafter 55 more fully described.

On the drawings:

Figure 1 is a front elevation of a printing and cap forming machine embodying the principles of this invention.

Figure 2 is a side elevation of the machine.

Figure 3 is an enlarged horizontal sectional view taken on line III—III of Figure 2.

Figure 4 is a horizontal sectional view taken on line IV—IV of Figure 2.

Figure 5 is an enlarged fragmentary detail section taken on line V—V of Figure 6, with parts shown in elevation.

Figure 6 is an enlarged vertical sectional view taken on line VI—VI of Figure 1.

Figure 7 is a fragmentary horizontal sectional view taken on line VII—VII of Figure 6.

Figure 8 is a fragmentary side elevation of the ink supply mechanism taken on line 75 VIII—VIII of Figure 3.

Figure 9 is an enlarged detail side view of the Geneva gear intermediate feed drive taken on line IX—IX of Figure 3.

Figure 10 is an enlarged top plan view of 80 the printing plate and its supporting roller.

Figure 11 is an enlarged fragmentary side elevation of a modified form of the ink supply mechanism which, in this instance, is adapted to be adjusted as a whole with respect to the printing roller or drum.

Figure 12 is a fragmentary front elevation of the modified form of ink supply mechanism illustrated in Figure 11.

Figure 13 is a fragmentary detail section 90 taken on line XIII—XIII of Figure 11.

As shown on the drawings:

The reference numeral 1 indicates a metal framework or base provided with a pair of parallel beams or supports 2, upon which 95 cross bars 3 are supported for the purpose of mounting a driving motor 4 in position. Secured on one end of the motor shaft is a driving pinion 5 which is in mesh with a spur gear 6 which is mounted on a clutch shaft 7, 100

5 journaled in suitable bearings secured on the framework 1. Mounted on the clutch shaft 7 adjacent one side of the spur gear 6, is a control clutch 8. The control clutch 8 is adapted to be operated by a lever or other suitable means to govern the starting and stopping of the machine.

10 Mounted on one projecting end of the clutch shaft 7 is a gear 9 which is in mesh with and drives a large spur gear 10. The large gear 10 is mounted on the outer end of a shaft 11, which is supported in suitable bearings 12 and 13, formed on upright frames 14 and 15, respectively. The frames 14 and 15 are supported upon the top of the framework 1, and are connected by means of a cross-bar or shelf 16.

15 Mounted upon the top of the shelf 16 is an inking attachment consisting of a pair of bracket plates 17 and 18, connected at their outer ends by means of an inclined cross-plate 19, having an adjusting screw 20 projecting through a threaded aperture therein. The inner end of the adjusting screw 20 is in contact with the bottom surface of an inclined wall 21, forming a part of an ink pot 22. The ink pot 22 is provided with a supporting flange 23, the ends of which are secured to the top edge of the cross-plate 19 by means of screws or the like. Rotatably mounted in the ink pot 22 is an ink supply roller 24, mounted on a shaft 25, the ends of which are journaled in bearings 26 secured upon the tops of the bracket plates 17 and 18. Secured on the shaft 25 adjacent the outer side of the bracket plate 17, is a ratchet 27 with which a pawl 28 coacts. The pawl 28 is pivotally mounted on the short arm of a bell-crank 29 which is pivotally mounted on the outer end of the shaft 25 adjacent the ratchet 27. The long arm of the bell-crank 29 is provided with a slot 30 through which a pin 31 projects. The pin 31 is carried transversely in the upper end of a link 32, the lower end of which is pivotally connected to a crank-arm 33 secured on one projecting end of a shaft 34, which is journaled in suitable bearings 35 formed on the bracket plates 17 and 18. Also keyed or otherwise secured on the shaft 34 intermediate the bracket plates 17 and 18 is a yoked crank-arm 36 which carries a roller 37 which has rolling contact with a control cam 38. The control cam 38 is supported on a cam shaft 39 which is journaled in bearings 40 formed on the bracket plates 17 and 18.

20 Also secured on the cam shaft 39 is an ink transfer control cam 41 with which a roller 42 is positioned to coact. The roller 42 is rotatably supported on a crank-arm 43. Integrally formed on the supporting shank 44 of the crank-arm 36 is a finger 45 to which one end of a coil spring 46 is attached. The lower end of the coil spring 46 is secured to a cross-plate 47 which forms a base connect-

ing the two bracket plates 17 and 18. The spring 46 acts to hold the roller 37 in resilient contact with the control cam 38. The base plate 47 is seated upon the top of the shelf 16 as illustrated in Figure 6. Mounted on the base plate 47 is an adjusting screw 48 which projects downwardly through a threaded opening in the base plate 47 and contacts with the upper surface of the shelf 16 to afford an arrangement whereby the ink pot and the ink transfer mechanisms may be raised and lowered with respect to the upright frames 14 and 15.

25 The crank arm 43 is integrally formed on a rocker bracket 49 having bearing sleeves integrally formed thereon. The rocker bracket sleeves are rotatably engaged on the shaft 34. Formed on the upper edge of the rocker bracket 49 are a pair of bearing yokes 50 in which a shaft 51 is journaled. Mounted on the shaft 51 between the bearing yokes 50, is an ink transfer or carrier roll 52 which is adapted at predetermined times to have rolling contact with the ink supply roller 24 to receive a supply of ink therefrom. At selected intervals the control cam 41 acting on the roller 42 serves to rock the rocker bracket 49 so that the ink transfer roll 52 is swung out of engagement with the ink supply roller 24 and into rolling engagement with an intermediate steel roller 53 which is supported on a shaft 54. The shaft 54 is slidably journaled in suitable bearings formed on the bracket plates 17 and 18, and has a gear 55 mounted on one projecting end thereof to the outside of the bracket plate 18 (Fig. 3). Secured on the opposite end of the shaft 54 to the outside of the bracket plate 17, is an inclined cam disc 56 which is in coacting relation with a beveled cam roller 57. The cam roller 57 is rotatably supported on a stub shaft 58 projecting from the outer face of the bracket plate 17. Also coacting with the cam roller 57 is an inclined cam disc 59 which is mounted on one projecting end of a shaft 60. The shaft 60 is slidably journaled in suitable bearings provided on the bracket plates 17 and 18, and carries another intermediate steel roller 61. Mounted above the two steel rollers 53 and 61, and in rolling contact therewith, is a composition inking roller 62 which is supported on a shaft 63, the ends of which are journaled in a pair of adjustable bearing brackets 64 mounted on projections 65 formed on the upper margins of the bracket plates 17 and 18. Each of the bearing brackets 64 is provided with a pair of adjusting screws 66 to permit the brackets 64 to be raised and lowered with respect to the bracket plate projections 65.

30 Mounted on one projecting end of the shiftable shaft 60 adjacent the outer side of the bracket plate 18 is a gear 67 (Fig. 3). The gears 55 and 67 are shiftable with the shafts 54 and 60, respectively, and mesh with an

intermediate gear 68. The gear 68 is mounted on one end of the shaft 39, and is driven by a large gear 69 which is supported on the shaft 11 to the inside of the upright bracket 15.

5 A composition ink supplying roller 70 has rolling contact with the intermediate ink transfer roller 61 and is mounted on a shaft 71, the ends of which are journaled in a hanger bracket 72 pivotally supported on a shaft 73 journaled in bearing extensions 74 formed on the bracket plates 17 and 18. The hanger bracket 72 is provided with upwardly projecting inclined arms 75 each of which carries an adjusting screw 76. The adjusting screws are adapted to coact with the edges of the bracket plates 17 and 18 to permit adjustment of the ink applying roller 70. The ink applying roller 70 is adapted to apply ink to a printing plate 77 which is mounted in a recess in the periphery of a printing roller 78 mounted on the shaft 11.

The printing plate 77 is adapted with each revolution of the printing roller 78 to print the type set-up carried thereon upon one surface of an intermittently advancing strip of paper 79 which is received from any suitable source of supply located at a convenient position above the machine. The strip of paper 79 is conducted downwardly around

30 the outer side of an upper guide roller 80 mounted on a shaft 81 journaled in a pair of upper bearing sleeves 82 formed on the upper edge of the upright frames 14 and 15. Mounted on the shaft 81 adjacent the inner side of one of the bearing sleeves 82 is a gear 83 which is in mesh with a gear 84 mounted on a shaft 85 which is journaled in bearing sleeves 86 also formed on the upright frames 14 and 15. Mounted on the shaft 85 between the upright

40 frames 14 and 15 is a feed roller 87 around the inner side of which the strip of paper 79 is conducted. Positioned adjacent the inner side of the feed roller 87 is an auxiliary feed roller 88 which is supported on a shaft 89, the ends of which are journaled in adjustable bearing blocks 90. The bearing blocks 90 are slidable in guide grooves 91 afforded by yokes 92 formed horizontally in the upper portions of the upright frames 14 and 15.

45 Closure blocks 93 carry adjusting screws 94 for adjusting the compression of springs 95 positioned between the bearing blocks 90 and the closure blocks 93. The strip of material 79 passes downwardly between the feed rollers 87 and 88, and then passes between the printing roller 78 and an auxiliary printing roller 95 which forms a backing or support for the strip of material when engaged by the printing plate 77. The auxiliary printing

55 roller 95 is supported on a shaft 96 which is journaled in bearings 97 formed on the upright frames 14 and 15. Mounted on the shaft 85 adjacent the inner side of the upright frame 15 is a gear 98 which receives a drive from a pinion 99. The pinion 99 is

mounted on a stub shaft 100 supported on the upright frame 15. Meshing with the pinion 99 to drive the same is a lower gear 101 which is supported on the shaft 96. The gear 101 is in mesh with a driving gear 102 mounted on the drive shaft 11 adjacent the ink roll drive gear 69. Meshing with the gear 84 is a gear 103 which is supported on the shaft 89 to cause rotation of the roller 88.

50 Mounted on the shaft 96 adjacent the outer side of the upright frame 14 is a Geneva gear 104 which coacts with and is intermittently operated by a second Geneva gear 105 mounted on the shaft 11 adjacent the outer side of the upright frame 14. It will thus be noted that the shaft 11 is adapted to be continuously rotated, while the material feed shaft 96 is intermittently operated to cause the material 79 to be intermittently advanced through the field of operation of the rotatable printing plate 77. The set-up carried by the printing plate 77 is thus adapted to be printed at spaced intervals along the strip of material.

55 After the strip of material is printed, said material is intermittently advanced through the field of operation of a cap blank punch and forming mechanism which will now be described.

60 Supported across the front of the machine by the upright frames 14 and 15, is a cross plate 106 provided with an aperture through which a punch sleeve 107 is adapted to be projected. Secured on the back of the plate 106 is a punch housing or sleeve 108 in which the punch sleeve 107 operates. Mounted on the outer face of the cross plate 106 is a die plate 109 which is provided with a punch receiving recess 110 which registers with the opening in plate 106. A diametric groove is provided between the plate 106 and the die plate 109 to permit the strip of material 79 to pass downwardly between the plates 106 and 109 to permit blanks to be punched from the material with each of said blanks having one surface thereof printed according to the set-up provided on the printing plate 77. Integrally formed within the die plate 109 is a circular rib or flange 111 which affords a restricted passage through which a punched cap blank is adapted to be forced by means of a cap forming plunger 112 which is slidably disposed within the punch sleeve 107. Removably engaged in a recess 113 formed in the outer face of the die plate 109 is one end of a cap receiving carton 114 which is supported on a bracket 115 secured to a front plate 116 fastened to the lower front edges of the upright frames 14 and 15. Formed on the inner end of the forming plunger 112 is a shank 117 of reduced diameter, having formed on the outer end thereof a pair of spaced lugs 118 (Fig. 5), which support a pin 119 on which a link 120 is pivotally engaged. A pin 121 projects through the outer end of the link 120 and has pivotally sup-

ported thereon the forked end of a bell-crank arm 122, the upper end of which is integrally formed on a bell-crank sleeve 123, which is rotatably mounted on a shaft 124 journaled in brackets 125 formed on the upright frames 14 and 15. Also integrally formed on the bell-crank sleeve 123 is a bell-crank arm 126 on the outer end of which a roller 127 is rotatably supported. The roller 127 tracks in a cam groove 128 formed in one side of a positive return cam disc 129 secured on the shaft 11.

Also secured on the shaft 11 is a blank punch control cam 130 on the periphery of which a roller 131 tracks. The roller 131 is rotatably mounted on one end of a bell-crank arm 132 which is integrally formed on a bell-crank sleeve 133 keyed on the shaft 124 adjacent one side of the bell-crank sleeve 123. Integrally formed on the bell-crank sleeve 133 is a second bell-crank arm 134.

Keyed on the shaft 124 adjacent the opposite end of the bell-crank sleeve 123 is a crank-sleeve 135 having a crank-arm 136 integrally formed thereon. The lower ends of the crank-arms 134 and 136 carry pins 137, the inner ends of which are pivotally engaged in a pair of parallel arms 138 which are integrally formed on opposite sides of a sleeve 139 secured in the outer end of the punch sleeve 107 and surrounding the shank portion 117 of the forming plunger 112. Coiled around the plunger shank 117 is a coil spring 140, one end of which seats against the inner end of the sleeve 139, while the other end seats against the inner end of the forming plunger 112 to resiliently hold said plunger in its normal retracted position in engagement with a stop ring or rib 141 which is integrally formed on the inner periphery of the punch sleeve 107. Normally, the punch sleeve 107 and the cap forming plunger 112, are in the retracted positions illustrated in Figure 6, to one side of the strip of material 79 which passes downwardly between the punch supporting plate 106 and the die block 109. After cap blanks have been punched from the strip of material 79, the perforated end of the material 79 passes downwardly between a pair of guide rollers 142 which are rotatably supported on the frame bars 2. After leaving the guide rollers 142 the perforated strip of material is coiled around a core 143 supported on a shaft 144 journaled in suitable bearings on the lower cross-bars of the framework 1. The shaft 144 and the reel core 143 mounted thereon are removable so that the reel of waste material 145 may be removed from the machine when necessary.

Figures 11, 12 and 13 illustrate a modified form of an ink supply mechanism adapted to be used in combination with the printing and cap forming machine in place of the inking mechanism illustrated and described in connection with Figures 1 to 10, inclusive.

In the modified form of the device the parts which are similar to those shown in Figures 1 to 10, inclusive, will be designated with corresponding reference numerals, and only the new parts will be identified by additional numerals. The modified form of inking attachment is adapted to be supported upon the shelf 16 and comprises a pair of brackets 146 provided with slots 147 (Figures 11 and 13), and with bearing sleeves 148. Journaled in the bearing sleeves 148 are stub shafts or pins 149 which project outwardly from side walls 150 mounted on the side margins of a supporting plate 151. The plate 151, together with the walls 150, afford a framework upon which the ink supply mechanisms are adapted to be supported. The framework supporting the ink supply mechanisms is pivotally supported by the pins 149 and is adapted to be adjusted with respect to the brackets 146 by means of clamping screws 152 which project through the slots 147 in the brackets 146, and have the inner ends thereof threaded into threaded openings provided in the walls 150. Also mounted on the plate 151 is a pair of brackets 153 connected by means of an inclined cross plate 154. The adjusting screw 20 and inclined wall 21 of the ink pot 22 are supported on the adjustable framework 150-151, as are also the various ink feed rollers and the mechanisms for operating the same. These various parts are indicated by the same numerals used in connection with Figures 1 to 10, inclusive, so that ink from the ink pot 22 may be supplied to the various intermediate rollers and evenly distributed to the ink applying roller 70 which, in turn, acts to apply an even coating of ink to the printing plate 77.

The operation is as follows:

A reel of material supported above the machine is adapted to be unreeled so that the strip of material 79 is conducted downwardly around one side of the guide roller 80 and then downwardly between the feed rollers 87 and 88, passing one side of the printing roller 95 and then continuing downwardly through the punch mechanism to be wound up on the reel core 143. The reel shaft 144 may be connected to receive an intermittent drive from the intermittently rotated shaft 85 permitting the punched out material to be intermittently wound on the reel core each time the material is advanced a predetermined amount.

The machine is started by shifting the clutch 8 to cause a drive to be transmitted from the motor 4 to the spur gear 6, thereby causing rotation of the shaft 7 and the gears 9 and 10. Rotation of the large gear 10 rotates the main shaft 11 and the gear 69 thereon to cause rotation of the intermediate gears 68, which in turn rotates both of the smaller shiftable gears 55 and 67 mounted on

the shiftable shafts 54 and 60, respectively. The ink distributing rollers 53 and 61 are thus continuously rotated and alternately shifted back and forth due to the action of the cam discs 56 and 59 which are actuated by the cam roller 57.

The gear 68 rotates the cam shaft 39, thereby causing the control cam 38 to act on the roller 37 to operate the bell-crank arm 36 and the bell-crank arm 33. The finger 45 formed on the bell-crank sleeve 44 is adapted to coat with the adjustable stop screw 48 to limit the swing of the bell-crank arms 36 and 33. Operation of the bell-crank arm 33 actuates the link 32, thereby causing the bell-crank 29 to be rocked whereby the pawl 28 acting on the ratchet 27 causes the ink supply roller 24 to be rotated a predetermined amount in the ink-pot 22 with each revolution of the shaft 39. The ink transfer control cam 41 coating with the roller 42 operates the crank-arm 43 and the bracket 49 to cause the ink transfer roller 52 to be alternately swung into engagement with the ink supply roller 24 and the intermediate ink distributing roller 53. The shiftable ink distributing roller 53 moves longitudinally with respect to the roller 52 so that the ink delivered by the roller 52 is evenly distributed over the peripheral surface of the roller 53. From the roller 53 ink is transmitted to the intermediate roller 62 and then to the shiftable ink distributing roller 61, which in turn delivers a supply of ink to the ink applying roller 70 with which it has rolling contact. The roller 70 is adapted to be adjusted with respect to the shiftable ink distributing roller 61 by means of the adjusting screw 76.

Ink from the applying roller 70 is adapted to be evenly applied to the type set-up carried on the printing plate 77 with each revolution of the printing roller 78.

As the material is advanced downwardly between the printing plate 77 and the printing roller 95, one surface of the strip of material 79 has printed thereon a notation corresponding to the set-up of the type carried on the printing plate. It will thus be noted that the intermittently advancing strip of material 79 is printed at spaced intervals and is intermittently advanced downwardly between the punch supporting cross-plate 106 and the die block 109. When a printed section of the material is properly centered in the punch mechanism, the punch control cam 130 operates the roller 131 and the crank-arm 132 causing the shaft 124 to be rocked, thereby causing the crank-arms 134 and 136 to be swung inwardly to operate the punch sleeve 107. The punch sleeve 107 coming into contact with the strip of material 79, punches out a printed cap blank and then advances the blank towards the ring 111. With the advance of the punch sleeve 107, the ring 141 in said punch sleeve causes the forming

plunger 112 to advance simultaneously with the punch sleeve. After a blank has been punched from the material the blank forming control cam 129 coating with the roller 127 causes the crank-arm 126 to be rocked upwardly, thereby causing the crank-arm 122 to be swung inwardly to actuate the connecting link 120, thereby causing the forming plunger 112 to be pushed outwardly beyond the end of the punch sleeve 107 to contact and force the cap blank through the forming ring 111, thereby causing the margin of the blank to be bent over to form a rim or flange. The formed cap when leaving the forming ring 111 is pushed into a receiving carton 114 which is supported in place on the bracket 115, with one end of the carton engaged in the die block 109.

With each rotation of the shaft 111 a printed cap blank is punched out of the strip of material and is forced through the forming ring and into the cap receiving carton 114. The printed caps are seated one within the other within the carton until a predetermined number of caps have been delivered, after which the filled carton may be removed from the carton supporting bracket 115 and a new carton substituted in place thereof.

The modified form of inking mechanism illustrated in Figures 11 to 13, inclusive, is adapted to be operated from the machine in a manner similar to the inking mechanism illustrated in Figure 6. In the modified form of inking mechanism a novel arrangement is provided, whereby the entire inking mechanism may be adjusted with respect to the machine frame by merely releasing the clamping screws 152 and tilting or adjusting the framework 150-151 about the pins 149, whereby the ink applying roll 70 may be adjusted with respect to the printing plate 77. After the pressure of the ink applying roll has been adjusted with respect to the printing plate and drum, the clamping screws 152 are tightened to hold the inking mechanism supporting framework in a predetermined position of adjustment. The modified mounting for the inking mechanism affords an arrangement whereby the entire inking unit may be conveniently adjusted with respect to the machine frame, and with respect to the printing drum, and furthermore, permits the inking unit to be conveniently mounted in place or removed as a unit to permit replacement of parts or repairs when necessary.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. In a cap printing and forming machine, means for intermittently advancing a strip of material past printing and punching stations, means at the printing station for printing a portion of the strip at said station, means at the punching station for punching a blank forming a portion of the strip previously printed by said printing means, and means actuated by the printing means for causing said punch means to be operated in timed relationship with the printing means, said punching means including forming means operative on the printed blank punched from the strip to form it into a flanged cap and to force the flanged cap clear of the punch means.
2. In a cap printing and forming machine, a printing device, a punching and cap forming mechanism, means for advancing a strip of material past the printing device to be printed thereby and then causing the printed material to be passed through the punching and cap forming mechanism, and means actuated by the printing device for causing operation of said mechanism in timed relationship with the printing device to cause a printed blank to be punched from the printed strip of material and then be formed into a flanged cap.
- 30 In testimony whereof I have hereunto subscribed my name at New York, New York County, New York.

CESARE BARBIERI.
